UNITED STATES PATENT OFFICE.

MAX SCHNEFEL, OF NEWARK, NEW JERSEY.

DESIGN FOR A CORN KNIFE OR SIMILAR ARTICLE.

Application filed August 15, 1922. Serial No. 3,389. Term of patent 7 years.

To all whom it may concern:

Be it known that I, MAX SCHNEFEL, a citizen of the United States, residing at Newark, in the county of Essex and State of New Jersey, have invented a new, original, and ornamental Design for a Corn Knife or Similar Article, of which the following is a specification, reference being had to the accompanying drawing, forming a part thereof.

The invention is clearly illustrated in said accompanying drawing, which shows my new, original, and ornamental design for the corn-knife, or similar article.

In said drawings, Figure 1 is a front view; Figure 2 an edge view; and Figure 3 a horizontal section, taken on line 3-3 in said Figure 1.

I claim:—

The ornamental design for a corn-knife or similar article, as shown.

MAX SCHNEFEL.
